CLAIM

The ornamental design for an electronic cigarette, as shown and described.

DESCRIPTION

FIG. 1 is a perspective view of an electronic cigarette; FIG. 2 is a front view of the electronic cigarette; FIG. 3 is a rear view of the electronic cigarette; FIG. 4 is a bottom side view of the electronic cigarette; FIG. 5 is a top view of the electronic cigarette; FIG. 6 is a left side view of the electronic cigarette; and, FIG. 7 is a right side view of the electronic cigarette. The evenly spaced broken lines in the drawings depict portions of the electronic cigarette that form no part of the claimed design; the dash-dot-dot lines represent boundary lines for the claimed design.

1 Claim, 7 Drawing Sheets

Related U.S. Application Data

division of application No. 29/662,843, filed on Sep. 10, 2018, now Pat. No. Des. 868,360, which is a division of application No. 29/592,199, filed on Jan. 27, 2017, now Pat. No. Des. 830,625.
